SAFETY RAZOR

William F. Steinmetz and Sol Rothschild,
New York, N. Y.

Application July 17, 1934, Serial No. 735,547

18 Claims. (Cl. 30—40)

This invention relates in general to safety razors and razor blades and more particularly to improvements in safety razors of the magazine type as well as an improved blade construction 5 which will be inherently suited for use in such types of razors.

We are aware that it is an old expedient to provide safety razors of the magazine type employing continuous or substantially continuous tape 10 blades. We are also aware that it has been previously suggested that such blades be wound and unwound upon spools so as to advance the blade into shaving position in the razor. Such a theoretical suggestion in the past has fallaciously 15 been predicated on the idea that as long as a thin blade is used, it may be sharpened to provide a suitable shaving edge and further the blade, be it of the ordinary material used in single straight safety razor blades, will have the required longitudinal flexibility and pliability to withstand the 20 strains imposed upon it in winding on spools of small diameters without cracking or rupturing. Such a fallacious theory has remained consistently previously unchallenged, or at least no one 25 to our knowledge has either challenged it or suggested the possibility or probability of such now seemingly obvious happening of breakage under such conditions, nor have they suggested anything upon which could be seized as a remedy 30 therefor.

The U. S. patent to Thompson 1,850,902 for Safety razor blade, March 22, 1932, deals with a single safety razor blade for a non-magazine type of razor. The blade herein is rendered for a part 35 of its end portions relatively pliable, the pliable portions being joined by a longitudinal slot. The purpose here of the slot and pliable portions is to render the blade, or rather its center portion, relatively more flexible and pliable transversely 40 than it otherwise would have been. This is a recognition of the strains imposed upon the blade in a transverse direction imposed by the clamping action of the blade holder.

The present invention is among other things 45 the result of appreciation, as a result of actual experience, of the necessity of rendering the blade inherently flexible longitudinally particularly when a blade of the tape type, whether continuous or substantially so, is used in a safety razor 50 of the magazine type.

One of the main objects of the invention is to provide a safety razor blade that will be inherently flexible and pliable longitudinally, whether the blade is of the single or tape type.

55 Another object of the invention is to provide a

safety razor blade, the main body portion of which will be longitudinally pliable or flexible throughout relatively to the blade cutting edge, whether the blade be of the single or continuous tape type.

Another object of our invention is to provide a safety razor furnished with a continuous longitudinally flexible tape blade that has a plurality of effective blade changes in one continuous length.

A further object of this invention is to provide a safety razor with a continuous longitudinally flexible tape blade that may be wound upon a spool to form an interchangeable cartridge for use in such a safety razor.

Another object of this invention is to provide a safety razor with a blade seat and guard which when the blade in its shaving position will hold the extreme cutting ends of the blade against the flat portion of the blade seat and also against the downwardly disposed ends so as to adapt the curved extended cutting edges of the blade to the more abrupt changes of the contours of the surfaces to be shaved.

The above and other features of this invention together with the various details of construction and combination of its parts will be now more particularly described by reference to the accompanying drawing and as pointed out in the claims. One form of this razor embodying our invention 25 is illustrated in the accompanying drawing, in which:

Figure 1 is a view in front elevation, partly in section of the razor;

Figure 2 is a view in top plan, partly in section of the razor;

Figure 3 is a view in side elevation of the razor, showing in dotted lines the open positions of the blade-clamp-cover and magazine door;

Figure 4 is a view in section taken along line 40 4—4 of Figure 1;

Figure 5 is a fragmentary view in perspective of the blade showing the same with its two extreme unsharpened ends or its leader and trailer provided with apertures for fastening same to 45 the spools;

Figure 6 is a view in perspective of the spool upon which the tape blade is wound, the showing of the blade being omitted;

Figure 7 is a perspective view of the spring-clip for retaining the blade upon the spool before loading the razor.

In the form of our razor illustrated the handle 50 has at its upper part a portion 11 extending laterally flat, forming the blade seat 13 having 55

a guard edge or a plurality of guard teeth at 14 to guard the shaving or cutting edge of the blade. The blade seat, as well as the guard is flat throughout except at each end which are curved 5 to provide curved shaving edges for the blade. The outer surfaces 14" of 14' of the guard ends are arranged so that the curved surface 14" has the same relation to the downwardly curved ends of the cutting edge portion 23 of the blade as the 10 guard 14 has to the straight portion of the blade. Thus the combination of guard 14' and the downwardly curved ends of cutting edge portion 23 of the blade forms a new and improved cutting edge for shaving the more abrupt changes in contour of the surfaces necessary to be shaved. The 15 cover 21, pivoted at 21', is also curved in conformity to the outer surfaces 14' and 14" to hold the blade in this desired position at its both ends.

The blade seat 13 is arranged with a channel 20 or recess 15, Figures 2 and 4, along its entire extent through which the back or unsharpened edge of blade 23 runs, and together with the idler sprockets 17 and 17' provided in the seat 13 act to guide blade 23 in its proper shaving position 25 laterally in relation to guards 14 and 14'. At the rear of the laterally extended portion 11 is a chamber 18 formed to provide a housing for up-standing lugs 19, integral with 11, and springs 20 secured to the clamp-cover 21 at 16. Springs 20, 30 in conjunction with lugs 19, act to cause the clamp-cover 21 to bear with pressure on the upper surface of the blade keeping it flat and tightly against its seat when cover 21 is in its closed position, and also act to keep the clamp-cover 35 21 in an open position when required for cleaning or reloading, springs 20 being arranged to exert pressure against the side or top of lugs 19 depending on whether clamp-cover 21 is in its closed or open position.

The blade seat 13, in part, is moulded into the handle 10 and forms the top enclosure of the blade chamber or magazine 25, Figures 1 and 4, together with the rear wall 42, the side walls 44 and 45, and the magazine door 32. This chamber or magazine 25 is shown in the uppermost part of the handle 10 and directly under the blade seat 13. It is to be understood that this blade chamber or magazine may be placed at other positions than that shown or that it may be separated into two chambers, if desired. Immediately under the guard teeth 14 and parallel therewith there is formed a drip 13', Figure 4, in order to prevent water from entering the blade chamber 25.

The blade chamber or magazine 25 is provided 55 with two rotary spindles 26 and 26', which are arranged to receive a winding spool 27 and an unwinding spool 27' respectively, which are locked in position on spindles 26 and 26' by springs 28 and 28', integral with the hubs 51 and 51', respectively, seating themselves by tension in the recesses 58 and 58' formed in the spindles 26 and 26' respectively, thus fixing the spools 27 and 27', respectively, securely in place.

The spools 27 and 27' are each constructed with 65 a flange 29 and 29', respectively, on one side only, which is disposed at right angles to the longitudinal axis of their hubs 51 and 51' respectively. These hubs are slightly wider than the width of blade 23 which is wound upon spools 27 and 27' with the unsharpened or back edge facing towards and touching flanges 29 and 29' respectively. Guiding idler sprockets 35 and 35', which engage the recesses or apertures 12 of the tape blade, are so positioned that the unsharpened or 70 back edge of the blade is kept in alignment with

flanges 29 and 29' respectively, thus preventing the cutting edge of the blade from contacting or touching any part of the handle 10 while being fed to its shaving position. The hubs 51 and 51' are flared outwardly at their ends 30 and 30', respectively, forming a hollow frustum of a cone which frictionally engages the conically formed bearings 31 and 31', respectively, projecting from and integral with the magazine cover 32 to set up a slight resistance to rotation of the spools 10 and avoid inadvertent movement thereof.

The magazine 25 and the magazine door 32 both extend outward and upward to the outermost ends of the blade seat 13 to the points 34 and 34', respectively, Figure 1, where the blade leaves and enters the magazine 25, being the outer longitudinal extremities of the shaving position of the blade, thus affording a protecting housing for all of blade 23 except that portion 15 in shaving position.

The magazine door 32 is so designed that its sides 44' and 45', Figures 1 and 3, form a portion of the sides of the magazine 25 when in its closed position, thus when the magazine door 32 is revolved to its full open position for renewing a cartridge of blade 23, loading of the razor is made convenient for the operator, as the sides 44' and 45' of magazine door 32 are then moved out of interfering position.

When a full cartridge or in other words spool 30 fully wound with the tape blade such as 27 in Figure 6 with a leader 36 and trailer 36', is put into the magazine 25, both the blade-clamp-cover 21 and the magazine door 32 are open. The cartridge is placed upon the top spindle 26. The leader 36 is shown integral with and as a continuation of the blade. The leader is formed without a cutting edge and is of sufficient length to enable the operator to thread the blade through its required path without handling a cutting edge 40 as the blade is drawn from the top spool 26 over the idler sprocket 35', over idler sprocket 17', through the guide channel 15 in blade seat 13, over the idler sprocket 17, over the idler sprocket 35, and over the outwardly disposed side of the 45 spindle 31 which may be preferably outwardly spring pressed. The leader as well as the trailer is provided with an aperture 41 or other means, for attaching the tape-like longitudinally flexible blade to lug 42, formed in hubs of the spools 50 51 and 51'. Figure 6 shows a typical spool. The spools 27 and 27' are duplicate in form. After the aperture 41 of the leader is placed on lug 42 of the winding spool 27' the blade is ready for winding. The magazine cover 32 is then revolved 55 to its closed position and the blade-clamp-cover 21 is then revolved to its closed position when the male members 38 formed on the outwardly disposed ends of the blade-clamp-cover 21 will engage with the female slots 39 provided 60 in the top of the sides of the magazine cover 32, thus locking the magazine cover 32 in its closed position.

The safety razor is designed to be compact and of a convenient useable size. It will thus be appreciated that with the use of an unwinding and winding spool, a blade seat and a guard and cover the blade will be subjected to severe bending strains as it travels through relatively acute angles. It is important then that the blade have 70 sufficient longitudinal flexibility to withstand such strains and at the same time maintain an efficient cutting edge, whether the main body portion is of the same or different material used in the cutting edge. Preferably an extraordinarily light 75

thin gauge steel is used for this purpose. Even then it is necessary to subject the main body portion, indicated at 23' in Figure 5, to a softening process as distinguished from the cutting edge, indicated at 23 in the same figure, the cutting edge not being subjected to such softening process. The treatment of the blade necessary to produce the relatively hard cutting edge portion longitudinally throughout the blade and the relatively soft, or pliable, main body portion 23' throughout depends upon the composition of the steel of which the blade is formed. In the event that carbon steel is used, the entire cutting edge may be given a proper cutting edge temper. Then by the use of cold clamps the cutting edge portion may be protected from the heat to which the main body portion is subjected for rendering the latter relatively soft or pliable while the temper of the cutting edge is undisturbed. The provision of the spaced apertures 12 also increase the longitudinal flexibility of the blade. The leader and trailer, having no cutting edge, are subjected in their entirety to the softening process.

The blade with its leader 36 and its trailer 36' have a plurality of equally spaced recesses or apertures 12 provided on a longitudinal axis to afford additional flexibility longitudinally, also, the said apertures 12 function as means to receive the teeth in the train of idler guiding sprockets 35, 35', 17 and 17' which keep the blade in shaving alignment.

Fixed to winding spindle 26' is a notched wheel 40 of such dimensions as to project beyond the side walls 44 and 45 of handle 10 which is arranged to be revolved counterclockwise, as viewed in Figure 1, by the operator furnishing the means to draw the first cutting edge into shaving position as indicated by numerals marked on the blade that register through the glass protected sight-hole 56, Figure 3, provided on the side of the magazine door 32. It is obvious that this wheel 40 is merely a means for conveying the blade from one position to another and suitable gears or other means for such conveying may be employed. To guard against the operator revolving the notched wheel 40 in a wrong direction for feeding the blade 23, a spring pawl 46, Figure 1, is provided to engage with same.

To retain the blade when wound upon the spool from springing open before it is loaded into the magazine a spring metal blade-clip, Figure 7, is provided which has a cross piece 60 with arcuate ends 61 and 62 and which is snapped over the wound blade thus holding it securely wound upon the spool. After the cartridge or fully wound spool is placed in its position in the magazine so that spring 55 engages against the wound blade and not the blade-clip, the latter is removed by the operator; spring 55 then assuming the function of this clip. Similarly a spring 55' is provided to engage against the blade being rewound on the winding spool 27'. When the entire length of the blade has been used and rewound on the winding spool 27' the operator places the blade-clip over the blade and removes the used cartridge from the handle.

We claim:

1. In combination in a razor, a perforated longitudinally flexible tape blade, a magazine for receiving a winding spool and a storage spool for said tape blade said spools having flanges one of which is inclined for maintaining said blade in alignment, said magazine having an inclined bearing surface frictionally engaged by said flanges.

2. In combination in a razor, a perforated longitudinally flexible tape blade, a magazine for receiving a winding spool and a storage spool for said tape blade, said spools having flanges one of which is inclined for maintaining said blade in alignment, said magazine having an inclined bearing surface frictionally engaged by said flanges, guiding means including idler sprockets adapted to engage the perforations in said blade.

3. In a safety razor, a longitudinally flexible tape blade, a magazine, a winding spool and a storage spool for said blade, each of said spools having on its hub a means of connection to the corresponding extremity of said blade, each of said spools having a pair of flanges one of which is outwardly inclined for centering said blade on said spool and preventing transverse movement of said blade on said spools.

4. In a safety razor, a longitudinally flexible tape blade, a magazine, a winding spool and a storage spool for said blade, each of said spools having on its hub a means of connection to the corresponding extremity of said blade, each of said spools having a pair of flanges one of which is outwardly inclined for centering said blade on said spool, resilient means carried by said magazine and bearing against said blade on said spools and on said blade between said spools for keeping said blade taut and from overrunning said spools.

5. In a safety razor, a longitudinally flexible tape blade, a magazine, a winding spool and a storage spool for said blade, each of said spools having on its hub a means of connection to the corresponding extremity of said blade, each of said spools having a pair of flanges one of which is outwardly inclined for centering said blade on said spool, a manually operated ratchet for winding said winding spool and a pawl for engaging said ratchet and preventing movement thereof in a reverse direction.

6. In combination in a safety razor, a continuous longitudinally flexible tape blade having a shaving edge, a blade seat flat throughout the major portion of its length and downwardly curved at either end, a clamping device including a cover for holding said blade in shaving position on said seat, means for advancing and guiding different effective lengths of said blade into shaving position, a protective guard for the shaving edge of said blade, said guard including downwardly curved guard ends at either end and said cover being correspondingly curved downwardly at each end to clamp the curved ends of said blade therebetween so as to protect the shaving edge of the adjacent downwardly curved ends of said blade and render the same effective for shaving purposes as well as the intermediate major flat portion of said blade on said seat.

7. In a safety razor, a continuous longitudinally flexible tape blade with perforations therein, a blade seat having a channel for guiding and positioning the blade, idler guide sprockets adjacent said blade seat adapted to engage the perforations and guide the blade into shaving position upon said blade seat and position it thereon, a guard edge and guard ends, associated with said blade seat, a blade clamp cover pivotally connected to said blade seat at the rear thereof, lugs carried by said razor rearwardly of said seat, springs attached to the blade clamp cover adapted to resiliently and frictionally engage said lugs said cover being adapted to simultaneously cover and engage said blade to hold the same securely in shaving position on said seat.

8. In a safety razor, a perforated longitudinally flexible tape blade, a channeled blade seat adapted to receive said blade in partially overlapping relationship for guiding and reinforcing said blade, blade engaging members fitted in said blade seat engaging the perforations for guiding and positioning said blade on said seat, idler sprockets adapted to engage the apertures of said blade and a blade clamping cover pivotally connected to said blade seat.
9. In a safety razor, a perforated continuous longitudinally flexible tape blade having a shaving edge, a flat blade seat provided with downwardly curved ends, a substantially flat blade clamp cover having downwardly curved ends to cover the blade and clamp the blade in shaving position on the flat and curved portions of said seat, idler guiding sprockets adapted to engage the perforations of said blade to position the blade on its seat, a protective guard edge for the shaving edge of said blade on said seat, said guard edge being provided with guard ends for guarding said blade at the extreme downwardly turned ends of said blade seat, said guard ends having the same relation to the curved portions of the shaving edge of the blade as the flat portion of the guard edge has to the intermediate straight portion of the shaving edge of the blade on said seat.
10. In a safety razor, a continuous longitudinally flexible tape blade, a winding and an unwinding spool, a magazine and means for mounting said spools therein, a spring blade clip adapted to fit over said unwinding spool and removable after said spool has been mounted in said magazine for maintaining said wound blade in position concentric on said spool.
11. In a safety razor, a longitudinally flexible tape blade, a spool upon which said blade is wound, a magazine and means for mounting said spool therein, a blade clip having portions adapted to removably fit over said spool and engage said blade thereon, a spring carried by said magazine and adapted to normally bear inwardly on the blade wound on said spool, and to also engage said blade between said clip portions while said clip is in engagement with said blade.
12. In a safety razor, a blade having a cutting edge, a blade seat, said seat being substantially flat longitudinally throughout the major portion of its length with an abruptly downwardly turned end, a clamping cover for clamping said blade flat against the flat portion of said seat and against the turned portion of said seat, a protective guard for the cutting edge of said blade on the flat portion and turned portion of said blade seat for rendering the flat and turned portion of the cutting edge on said seat available for shaving purposes.
13. In a safety razor, a plurality of longitudinally arranged effective razor blade shaving edges, a blade magazine, a blade seat, a clamping cover positioning means in said seat in addition to said cover for maintaining said blade on said seat, means for feeding said effective shaving edges from said magazine to said positioning means, said blade seat being substantially straight longitudinally throughout the major portion of its length with abruptly downwardly curved ends, said clamping cover holding said blade flat against the flat portion of said seat and against the curved portions of said seat, and a protective guard in alignment with the curved and flat portions of said blade seat for guarding the clamped straight and curved portions of the shaving edge of the blade on said seat.
14. In a safety razor, a plurality of longitudinally arranged effective cutting edges, a blade seat, said seat being substantially flat longitudinally throughout the major portion of its length with abruptly curved ends, a clamping cover for clamping an effective cutting edge flat against the flat portion of said seat and against the curved portions of said seat, a protective guard for the effective cutting edge of said blade on the flat and curved portions of said blade seat for the purpose of rendering the flat and curved portions of said cutting edge on said blade seat available for shaving purposes.
15. A flexible safety razor blade adapted to be bent longitudinally when clamped in its holder, said blade being resilient as a whole to the extent that it will resume substantially a flat condition when unclamped, having a longitudinally extending hard cutting edge, substantially all of the remaining body portion of the blade being of a material inherently relatively softer than said cutting edge to form continuous chains of flexing hinges in a transverse and in a longitudinal direction substantially the entire width and length of said body portion so as to render said blade flexible in both of said directions without danger of fracture when clamped in a razor subjecting said blade to the strain of flexing in either or both of said directions about abrupt turns.
16. A flexible continuous tape safety razor blade adapted to be bent longitudinally when clamped in its holder, said blade being resilient as a whole to the extent that it will resume substantially a flat condition when unclamped, having a longitudinally extending hard cutting edge, substantially all of the remaining body portion of the blade being of a material inherently relatively softer than said cutting edge to form continuous chains of flexing hinges in a transverse and in a longitudinal direction substantially the entire width and length of said body portion so as to render said blade flexible in both of said directions without danger of fracture when clamped in a razor subjecting said blade to the strain of flexing in either or both of said directions about abrupt turns.
17. In combination in a razor, a continuous longitudinally flexible tape blade, a blade seat, means including a winding and an unwinding spool for advancing said blade on said seat, guide members for guiding said blade, said blade having markings thereon indicating different effective lengths of said blade, a fixed restricted aperture in said razor through which said markings on said blade are made visible as said winding and unwinding means advances said blade on said seat, said aperture acting as an indicating means for registering when said different effective lengths of said tape blade are in proper shaving position on said seat.
18. In combination in a razor, a perforated longitudinally flexible tape blade, a magazine for receiving a winding spool and a storage spool for said tape blade, each of said spools having flanges one of which is smaller than the other so that said blade may be wound upon either of said spools with its cutting edge free of any bearing surface and said smaller flanges being so disposed as to maintain said blade in alignment on said spools.

WILLIAM F. STEINMETZ,
SOL ROTHSCHILD.
